AGITATOR

Joseph M. Pryor and Bruno Cescato, Chicago, Ill.

Application July 13, 1946, Serial No. 683,341

5 Claims. (Cl. 259—102)

1

This invention relates to agitating apparatus, and more particularly to apparatus adapted to agitate material within a drum or other container, as in a paint drum.

One feature of this invention is that it provides improved agitating apparatus, and more particularly means for initially moving or loosening material at the bottom of a container and then for carrying it on up and thoroughly intermixing it through the remainder of the container; another feature of this invention is that it provides lower agitating means rotatable about a vertical axis and preferably disposed angularly of said axis; a further feature of this invention is that it provides upper agitating means rotatable about a horizontal axis above said lower means; yet a further feature of this invention is that it provides common drive means for rotating said lower and upper agitating means; and still another feature of this invention is that it provides agitating apparatus which is readily and easily assembled within a drum of the conventional type without riveting, screwing, or bolting parts together after the drum is assembled, for the apparatus is so designed that all the parts fit together and are held in position upon assembly of the drum. Other features and advantages of my invention will appear from the following specification, and from the drawings, in which:

Fig. 1 is a vertical section through a drum including my improved agitating apparatus; Fig. 2 is a horizontal section through the apparatus shown in Fig. 1, taken on the line 2—2 of Fig. 1; and Fig. 3 is a vertical fragmentary sectional view taken along the line 3—3 of Fig. 1, with the operating crank removed and a cap inserted to seal the drum.

Materials such as paint are often stored in relatively large containers, as for example, 55 gallon drums, and while so stored the lead or other heavy portions of such material separate from the oils or lighter portions and settle at the bottom of said drum, while the oils rise to the top. Consequently, before such materials can be used after standing in the drum, the lead and oils must be stirred into a generally homogeneous mixture. In a large size drum containing paint this necessary mixing is a difficult and time-consuming task, and various attempts have been made to provide means whereby complete mixing can be obtained with a minimum of time and labor. Prior art devices for this purpose usually comprise one or more spiral blades extending vertically through the drum and rotatable about a vertical axis therein. Such devices, while facilitating the mix-

2

ing to a great extent, still require a great deal of labor and an excessively long mixing period before the heavy lead at the bottom of the drum is completely mixed with the oil.

We have devised and are here disclosing and claiming agitating apparatus which represents a distinct improvement over all such prior art devices, and comprises lower agitating means rotatable about a vertical axis and positioned angularly thereto, and upper agitating means comprising a plurality of paddle blades rotatable about a horizontal axis above said lower agitating means. Rotation of the lower agitating means lifts the lead or other heavy portion of the material to be agitated from the bottom of the drum where it is stirred into a generally homogeneous mixture with the oil by the upper agitating means. A cheap and simply constructed common drive mechanism is provided whereby both lower and upper agitating means may be rotated together. Our invention constitutes a further improvement over the prior art in that the parts fit together and hold themselves in position when the drum is completely assembled without using rivets, bolts, or similar fastening means.

Referring now to the drawings, a drum is indicated generally at 10, such drum being of the conventional type used to contain paint or similar material, and adapted to contain a relatively large amount of paint or other material to be stirred. The drum includes the generally cylindrical side wall 11, the bottom 12 and the top 13. Near the bottom of the side wall 11 is the bung hole 14 fitted with a threaded stopper or cap 15 so that the paint or other material may be withdrawn from the drum when desired.

The bottom and top portions 12 and 13 are conventionally secured and sealed to the side wall of the drum by means of the rolled or spun seam, as shown at 16 in Fig. 1, such seam extending completely around the periphery of each of said bottom and top portions. The bracket 17 is welded or otherwise secured near the center of the bottom portion 12, and the bracket 18 is similarly welded or otherwise secured near the center of the top portion 13, such brackets each being provided with an opening near the center, and the top portion 13 also being provided with an opening in alignment with said bracket openings, such opening in the top portion being threaded and removably fitted with the cap 19 for a purpose to be hereafter described.

A vertical shaft 20 is rotatably inserted in the openings in the brackets 17 and 18, said shaft bearing on the bottom 12 and extending up

through the drum to a point adjacent the hole in the top 13. The shaft is thus supported by the brackets 17 and 18, is rotatable in the holes in such brackets, and the upper portion of said vertical shaft is adapted to cooperate with a rotating member, as the crank 21, shown in Fig. 1, which crank is adapted to be placed in operative position when the cap 19 is removed from sealing relation.

Adjacent the bottom 12 is the lower agitating means, comprising the twisted blade 22 which is welded or otherwise secured to the vertical shaft 20 and is adapted to rotate therewith. Such blade is twisted at such an angle that upon forward rotation of the handle 21 (forward rotation in this specification being defined as clockwise rotation while looking down on the drum), the blade 22 rotates adjacent the bottom 12, and the sloping angle of the front face 22a of the blade forces the material to be stirred up from the bottom of the drum.

The vertical shaft 20 is encased for a portion of its length by the sheath 23, which sheath is held against rotation by the bracket 24. Such bracket is welded or otherwise fixedly secured to the upper end of the sheath and has two oppositely disposed upstanding portions which cooperate with the bracket 18, as shown best in Fig. 3, in such manner that the sheath is held against rotation. Near its lower end the sheath carries the arm 25, which is fixed securely to the sheath and extends horizontally on opposite sides thereof, and near each end of which are rotatably mounted the multibladed paddle members 26 and 27, in the particular embodiment of our invention shown here, although it is to be understood that one such member is generally sufficient. The pins 28 extend through holes in the arm on either side of each paddle member to hold the paddle members in the desired position on the arm.

In the particular embodiment of our invention which is illustrated in the drawings each paddle member is shown as having four blades arranged at right angles to each other, such blades being designated as 26a, 26b, 26c, 26d, and as 27a, 27b, 27c, 27d, and each blade has a forwardly projecting right angular flange at its outer end, such flanges being shown in Figs. 3 at 26a', 26b', 26c', 26d', and at 27a', 27b', 27c', 27d'. The 50 sheath 23 terminates below the point of attachment of the arm 25, and is supported by the rotating arms 30, 31, 32, and 33, which are welded or otherwise fixedly secured to the shaft 20, and extend horizontally therefrom and at right angles to each other.

It will be readily seen that upon rotation of the shaft 20 in a forward direction, the lower agitating blade 22 will rotate forwardly about a vertical axis, and the arms 30 to 33 inclusive will also rotate and will cooperate with the multi-bladed paddle members to rotate such paddle members forwardly about the horizontal axis formed by the supporting arm 25. We have found that by using our new agitator a large 60 drum of paint (as for example a 55 gallon drum) may be stirred into a generally homogeneous mixture in a fraction of the time used by any prior art apparatus.

Furthermore, our improved agitating apparatus is so constructed that it may be easily assembled in a drum. In assembling such apparatus, the bracket 17 may be secured to the bottom 12 and the bottom then affixed to the drum. The agitating apparatus may then be inserted 70

into the drum, the shaft 20 extending through the hole in the bracket 17 and bearing against the bottom 12. Before the top 13 is affixed to the drum the bracket 18 is welded or otherwise secured to such top, and the top may then be put on the drum, the upper portion of the vertical shaft 20 extending through the hole in the bracket 18 to hold the agitating apparatus in position, and the bracket 24 cooperating with the bracket 18 to hold the sheath against rotation.

While we have shown and described a certain embodiment of our invention, it is to be understood that it is capable of many modifications. Changes, therefore, in the construction and arrangement may be made without departing from the spirit and scope of the invention as disclosed in the appended claims.

We claim:

1. In a container having top and bottom portions, agitating apparatus of the character described, including: a rotatable shaft extending vertically between said top and bottom portions and adapted to be rotated by means without the container; first agitating means rotatable with said shaft about a vertical axis; second agitating means rotatable about a horizontal axis; means for supporting said second agitating means; and means for rotating said second agitating means upon rotation of the shaft, such rotating means comprising at least one arm carried by said shaft and operatively engaging said second agitating means.

2. In a container having top and bottom portions, agitating apparatus of the character described, including: a rotatable shaft extending vertically between said top and bottom portions and adapted to be rotated by means without the container; lower agitating means rotatable with said shaft about its vertical axis; a sheath enclosing at least a portion of said shaft; upper agitating means supported by said sheath and being rotatable about a horizontal axis above said lower agitating means; means for holding said sheath against rotation; and means for rotating said second agitating means upon rotation of the shaft, such rotating means comprising at least one arm carried by said shaft and operatively engaging said upper agitating means.

3. In a container having top and bottom portions, agitating apparatus of the character described, including: a rotatable shaft extending vertically between said top and bottom portions and adapted to be rotated by means without the container; bracket means secured to said top and bottom portions for supporting and guiding said shaft; lower agitating means adjacent said bottom portion, such means comprising a blade member secured to said shaft and rotatable therewith, at least a portion of such blade member being angular to the vertical axis of said shaft; a sheath enclosing at least a portion of said shaft; upper agitating means supported by said sheath and being rotatable about a horizontal axis above said lower agitating means; means secured to said sheath and cooperating with at least a portion of said bracket means for holding the sheath against rotation; and means for rotating said second agitating means upon rotation of the shaft, such rotating means comprising at least one arm carried by said shaft and operatively engaging said upper agitating means.

4. In a container having top and bottom portions, agitating apparatus of the character described, including: a rotatable shaft extending

vertically between said top and bottom portions and adapted to be rotated by means without the container; bracket means secured to said top and bottom portions for supporting and guiding said shaft; lower agitating means adjacent said bottom portion, such means comprising a blade member secured to said shaft and rotatable therewith, at least a portion of such blade member being angular to the vertical axis of said shaft; a sheath encasing the upper portion of said shaft; upper agitating means supported by said sheath, said upper agitating means comprising at least one multibladed paddle member rotatable about a horizontal axis above said lower means, said paddle blades having forwardly projecting flanges; means secured to said sheath and cooperating with at least a portion of said bracket means for holding the sheath against rotation; and means for rotating said second agitating means upon rotation of the shaft, such rotating means comprising at least one arm carried by said shaft and operatively engaging said upper agitating means.

5. In a drum having a top and bottom agitating apparatus of the character described, including: a rotatable shaft extending vertically between said top and bottom portions and adapted to be rotated by means without the container; bracket means secured to said top and bottom portions for supporting and guiding said shaft; lower agitating means adjacent said bottom portion, such means comprising a blade

member secured to said shaft and rotatable therewith, at least a portion of such blade member being angular to the vertical axis of said shaft; a sheath encasing the upper portion of said shaft; upper agitating means supported by said sheath, said upper agitating means comprising a plurality of multibladed paddles rotatable about a horizontal axis above said lower means, said paddle blades having forwardly projecting flanges; means secured to said sheath and cooperating with at least a portion of said bracket means for holding a sheath against rotation; and means for rotating said second agitating means upon rotation of the shaft, such rotating means comprising a plurality of arms carried by said shaft and operatively engaging said paddle blades.
